DETERMINATION OF MINUTE TRACES OF WATER BY USE OF METHYLENE BLUE

Florence Nesh, 164 Hart St., Brooklyn 6, N.Y.

No Drawing. Filed Sept. 24, 1956, Ser. No. 611,796

4 Claims. (Cl. 23—230)

(Granted under Title 35, U.S. Code (1952), sec. 266)

The invention described herein may be manufactured and used by or for the Government of the United States of America for governmental purposes without the payment of any royalties thereon or therefor.

The present invention concerns a composition and method for determination of minute traces of water in materials that contain no water molecules or potential water molecules as a basic part of its structure. In particular the invention relates to a composition and method for determination of minute traces of water in materials such as jet fuel by use of an indicator such as methylene blue.

An object of the invention is to provide a simple and sensitive composition and method for determination of minute traces of water in materials in cases where drying methods cannot be used.

Another object is to provide a composition and method for determination of minute traces of water in material such as jet fuel by use of an indicator such as methylene blue.

Another object is to provide an indicator composition for detecting minute traces of water in a methylene blue inert material such as jet fuel in which the composition comprises a methylene-blue-inert solvent that forms a solution in which the water is less soluble than in the material alone, and the composition further comprises an admixture of methylene blue.

Another object is to provide a method for determination of minute traces of water in a methylene-blue-inert material such as jet fuel which comprises releasing the water by dissolving a sample of the material in a methylene-blue-inert solvent to form a solution in which the water has decreased solubility and whereby the water coagulates in globules, and then exposing the released water to methylene blue indicator.

Other objects and many of the attendant advantages of this invention will be readily appreciated as the same becomes better understood by reference to the following detailed description.

The determination of minute traces of water, especially in cases where drying methods cannot be used, has been difficult in the past and has involved the use of long procedures and complicated and unwieldy apparatus. These difficulties are overcome by the present invention which provides a simple and very sensitive composition and method making use of an indicator such as methylene blue that has extreme solubility in water.

The determination may be made, for example, by dissolving one volume of sample material such as jet fuel in two volumes of solvent such as carbon tetrachloride and a small quantity of methylene blue. Water present coagulates in globules and causes the methylene blue to turn from reddish-brown to deep blue.

The composition and method are particularly applicable to determination of minute traces of water in a material such as jet fuel or a solid such as hexachlorethane, although it can also be applied to other

2

materials. A preferable solvent with jet fuel and hexachlorethane is carbon tetrachloride, although other solvents such as acetone and benzol can be used provided that they do not react with the indicator being used and they do not react with the material being tested and furthermore that with jet fuels and hexachlorethane they form a solution with the material in which the water is less soluble than it is with the material alone. The indicator used is preferably methylene blue because of its extreme solubility in water and because of the fact that it does not react on materials such as jet fuel and hexachlorethane and furthermore it does not react with solvents such as carbon tetrachloride, acetone and benzol. Indicators other than methylene blue can be used so long as they are extremely soluble in water and have a high sensitivity thereto, and provided that they furthermore do not react with the material being tested and do not react with the solvent used.

In application of the invention to materials such as petroleum and hexachlorethane a determination is made by dissolving a sample of the material to be tested in a suitable solvent and adding the indicator. For example jet fuel is dissolved in carbon tetrachloride and methylene blue is added. Water present in the sample tends to be released due to decreased solubility of the water in the mixture of jet fuel with carbon tetrachloride. Upon release the water coagulates in globules. If the indicator is methylene blue, it is a dry, water soluble, reddish-brown powder in the carbon tetrachloride before formation of water globules and it turns a deep blue upon formation of the globules thus indicating the presence of water.

Example 1

One volume of jet fuel, Navy Grade JP-5 or heavy end fuel HEAF is dissolved in two volumes of carbon tetrachloride and a small quantity such as 10 mg. of dry methylene blue, water soluble, technical, Fisher Cat. No. A-766 is added. Water present in the sample tends to be released due to decreased solubility in the mixture of jet fuel and carbon tetrachloride and the water coalesces in globules. The methylene blue which remains as a reddish-brown powder in the carbon tetrachloride will turn a deep blue as globules form indicating the presence of water. The saturation point of the jet fuel used in this example had been carefully studied and determined to be about at 0.011% water. Various volumes of this water-saturated jet fuel were dissolved in carbon tetrachloride and methylene blue added. As little as 0.08 mg. of water, representing 0.000016% on the basis of a 500 gm. sample were indicated by the methylene blue. The dry jet fuel when dissolved in the carbon tetrachloride showed no reaction with methylene blue.

Example 2

One volume of turbine oil is dissolved in two volumes of carbon tetrachloride and a small quantity such as 10 mg. of dry methylene blue, water, soluble, technical, Fisher Catalogue No. A-766 is added. Water present in the sample tends to be released due to decreased solubility in the mixture of turbine oil and carbon tetrachloride and the water coagulates in globules. The methylene blue which remains as a reddish-brown powder in the carbon tetrachloride will turn a deep blue as globules form indicating the presence of water. Various samples of turbine oil containing different quantities of water were tested and as little as 0.03 mg. of water was detected. The dry turbine oil when dissolved in the carbon tetrachloride showed no reaction with the methylene blue.

Example 3

One volume of the sample of hexachlorethane which

has a limit of 0.05% water is dissolved in two volumes of carbon tetrachloride and a small quantity, approximately 10 mg. of dry methylene blue, water soluble, technical, Fisher Cat. No. A-766 was added. Water present in the sample tends to be released due to decreased solubility in the mixture of hexachlorethane and carbon tetrachloride, and coagulates in globules. The methylene blue which remains as a reddish-brown powder in the carbon tetrachloride will turn a deep blue as globules form indicating the presence of water. This indication will appear with as little as 0.03 mg. of water.

Obviously many modifications and variations of the present invention are possible in the light of the above teachings. It is therefore to be understood that within the scope of the appended claims the invention may be practiced otherwise than as specifically described.

I claim:

1. A method for determining the presence of trace amounts of water in a liquid material to be examined and that contains no water molecules and no potential water molecules as a basic part of its structure, which comprises adding to said material anhydrous carbon tetrachloride in a quantity sufficient to free any water that is incorporated in said liquid material, agitating this mixture to free any water incorporated therein, and then adding to the mixture a small quantity of dry, water soluble, methylene blue, whereby any water released from said liquid material will dissolve said methylene blue and change its color to a deep blue.

2. A method for determining the presence of trace amounts of chemically uncombined but physically entrapped water in a material to be examined and that contains no water molecules and no potential water molecules as a basic part of its structure, which consists essentially in establishing intimate physical contact of said material with anhydrous carbon tetrachloride, in a quantity sufficient to release any water that is physically entrapped in said material, and a small quantity of

dry, water soluble, methylene blue, whereby any water released from its physical entrapment in said material will dissolve said methylene blue and change its color to blue.

3. A method for determining the presence of trace amounts of water in a liquid petroleum compound that contains no water molecules and no potential water molecules as a basic part of its structure, which comprises bringing said petroleum into intimate contact with carbon tetrachloride in an amount sufficient to free any water incorporated in said petroleum, and a small quantity of dry, water soluble methylene blue, whereby the water released from said petroleum by said carbon tetrachloride will dissolve said methylene blue and change its color to its deep blue.

4. The method according to claim 2 wherein the contact of the material with the methylene blue occurs after the contact of the material with the carbon tetrachloride.
